(Cl. D91—3)

To all whom it may concern:

Be it known that I, Frederick L. Beebee, a citizen of the United States, residing in Manhattan Beach, in the county of Los Angeles, State of California, have invented a new, original, and ornamental Design for a Shower Head or Similar Article, of which the following is a specification, reference being had to the accompanying drawing, forming a part thereof.

I claim:

The ornamental design for a shower head or similar article, as shown.

FREDERICK L. BEEBEE.
